[57] CLAIM

The ornamental design for a marine depth sounder, substantially as shown and described.

DESCRIPTION

FIG. 1 is a top and right front perspective view of a marine depth sounder showing our new design;

FIG. 2 is a front elevational view thereof.

FIG. 3 is a right side elevational view thereof.

FIG. 4 is a rear elevational view thereof.

FIG. 5 is a left side elevational view thereof.

FIG. 6 is a top plan view thereof, the bottom view being a mirror image;

FIG. 7 is a top and right front perspective view of another embodiment of our view design of FIGS. 1-6;

FIG. 8 is a front elevation view thereof.

FIG. 9 is a right side elevational view thereof.

FIG. 10 is a rear elevational view thereof.

FIG. 11 is a left side elevational view thereof.

FIG. 12 is a top plan view thereof.

FIG. 13 is a bottom plan view thereof.
